UNITED STATES PATENT OFFICE.

WILLIAM M. TATE, OF ZANESVILLE, OHIO.

IMPROVED MACHINE FOR FILLING BOTTLES.

Specification forming part of Letters Patent No. 40,516, dated November 3, 1863.

To all whom it may concern:

Be it known that I, Dr. WILLIAM M. TATE, of Zanesville, in the county of Muskingum and State of Ohio, have invented a new and useful Machine for Filling Bottles with Oil and other Similar Fluids; and I do hereby declare that the following is a full, clear, and exact description of the construction and operation of the same, reference being had to the annexed drawings, making part of this specification, in which—

Figure 1 is a front elevation, and Fig. 2 is a side elevation, in which—

A A A is the frame of the machine; B B, upright stands for carrying the lever and spring; C, table supported by three legs, D D; E, plunger working into a cylinder with a funnel-shaped top; F, cylinder terminating at the bottom with a small nozzle to fit the bottles; G, lever for purposes of forcing down the plunger; H, spring for withdrawing plunger. Plunger E has a small hole running perpendicularly through it, which is open when it first is pressed down and then closed with a small plug. (Not shown in the drawings.) I is a bottle in position for receiving oil; K, a block or frame around the cylinder to keep the same in place.

The mode of operating the machine is as follows: The reservoir or cylinder F (the tube at the bottom being first closed by a cork or in some other suitable manner) is filled nearly full of oil or other similar fluid, and the plunger E, placed on the surface of the oil, with the small hole through the plunger open. Pressure is then applied to the lever G before the cork at the bottom is removed, and the plunger pressed down a short distance into the cylinder, by means of which a small portion of the oil will arise either through the hole in the plunger or along its side, and

will remain on the top of the sides of the plunger. The hole in the plunger is stopped, and the cork from the bottom removed, immediately after the spring H has lifted the plunger, which it does as soon as the pressure from the lever is removed. The bottle I is then placed under the tube at the bottom of the cylinder or reservoir, pressure applied to the lever until the bottle is filled, when pressure is removed and the spring elevates the plunger. The filled bottle is then removed, another empty one is placed under the tube, and the same process is repeated until the reservoir or cylinder is empty, when it is again filled and the process repeated as long as necessary.

It is perhaps necessary to say that after the reservoir or cylinder is filled and the plunger makes its first descent into it, and the small hole in the plunger stopped, as above described, the attraction or cohesion of the face of the plunger on the surface of the oil, or the removal of the pressure of the atmosphere from the surface of the oil, or some other thing not perhaps sufficiently understood by myself to describe, prevents the oil from exuding or coming out of the tube, during the time it takes to remove a full bottle and replace it with an empty one.

What I claim as my invention, and desire to secure by Letters Patent, is—

The arrangement and combination of the spring, lever, plunger, and cylinder described, and the other parts of the machine by which the effect is produced, substantially as set forth.

WILLIAM M. TATE.
